UNITED STATES PATENT OFFICE.

ROBERT GLADSTONE WELLS, OF MARPLE, ENGLAND.

INTERNAL-COMBUSTION ENGINE.

1,424,965.

Specification of Letters Patent. Patented Aug. 8, 1922.

Application filed January 4, 1921. Serial No. 434,960.

To all whom it may concern:

Be it known that I, ROBERT GLADSTONE WELLS, a subject of the King of England, residing at Marple, in the county of Cheshire, England, have invented certain new and useful Improvements in Internal-Combustion Engines, of which the following is a specification.

This invention relates to internal combustion engines of the "two-stroke" type and it has for its principal object to provide means for controlling the power thereof in such manner that the engine can be started with ease, and is capable of running efficiently at low speeds, either idle or during the performance of work. An important feature is that the manner of control does not adversely affect the scavenging action which takes place during mixture transfer, thereby avoiding the common ignition troubles known as "four-stroking" which arise when two-stroke engines are throttled, and thus promoting fuel economy.

According to this invention, the full working charge is at all times delivered to the working end of the cylinder but any desired proportion of it is returned before ignition takes place, to the charge pump or its equivalent, by the agency of a control valve, or valves, which may be hand or mechanically operated or a combination of both methods may be employed. Thus the usual scavenging action of the incoming charge is regularly carried out, the mixture ratio is adjusted before transfer but the quantity is not throttled nor otherwise varied, so that the power output may be determined solely by the quantity of mixture retained for ignition during the working stroke. In this way a reduced compression results for starting and slow running, but combustibility of the charge, and thus also the economy of the engine, is not adversely affected by the presence of a large proportion of inert gases as frequently occurs with the usual control system of throttling the mixture before entry into the charge pump.

The invention may be carried out in a variety of ways each characterized by the employment of a valve controlled conduit connecting the working end of the cylinder with the charge pump, or in the usual type of engine, with the crank chamber equiva-

lent thereof. Through this conduit a portion of the working charge is returned from the cylinder by means hereunder described.

The valve employed to control this return of the working mixture may be either mechanically or automatically operated by the engine with means for closing it at any desired point in the in-stroke of the piston previous to its reaching the earliest point at which ignition should occur.

In engines where the transfer of the charge is regulated by valves, such valves may be mechanically operated, and adjustable in such manner as to delay the time of closure to any desired point during the piston's in-stroke. The same end may be obtained with an engine employing an automatic valve in the transfer port, by the addition of an adjustable engine-actuated control device adapted to delay similarly the closure of the valve until the desired amount of the charge has been expelled from the cylinder.

The manner of carrying out the invention is shewn in the accompanying drawings illustrating in outline two example applications of this invention, wherein

Figure 1 is a central sectional view of the part of the charge return conduit in which the control valve is located between two ports communicating with the cylinder,

Fig. 2 is a central section through the cylinder and crank case of an engine, showing the control valve and the associated parts (with slight modifications) applied to it.

Referring first to Figure 1, the charge return conduit A is situated lengthwise along the outside of the cylinder, the working space of which is indicated at B. A port A² in the wall of the cylinder for the expulsion of the charge from the cylinder communicates with this conduit and is so situated that the working piston covers it when the minimum charge desired is present in the cylinder. The conduit is bored from the combustion chamber end to a point somewhat beyond the port A², for the reception of a piston valve C, preferably of the trunk pattern. The skirt of this piston is adapted to overrun the port A² to cut off communication of cylinder and conduit, and, if desired the edge C² of the skirt may be coned to correspond with a coned seating

A³, formed around the wall of the conduit A to receive it when the port is closed, and thus to promote pressure-tightness.

A port A⁴ also is formed to put the space on the other side of the piston valve C in communication with the combustion chamber B², and a cap A⁵ which closes the end of the return conduit A is provided with a stop A⁶ to prevent the piston valve from overrunning and covering this port A⁴. This latter alternatively may, if desired, be so situated that the working piston covers it for a certain period of its in-stroke.

Normally the piston valve C is thrust by a spring, such as the coil spring C³ against the stop A⁶, so that the charge-return port A² is uncovered. A second spring C⁴ whose loading can be varied as desired by a convenient form of hand controlled mechanism, such as the cable mechanism C⁵, acts in opposition to the first mentioned spring C³, so that if loaded sufficiently it can overcome it and hold the piston valve C so that the charge-return port A² is kept either partially or wholly closed.

In action, the loading of the piston valve C through the spring C⁴ is adjusted by the control means C⁵ as desired, as for example to ensure a low compression at starting, the working charge is transferred to the cylinder in the known manner, and thereafter, during the compression stroke of the working piston, some of the charge is returned through the valve-controlled port A² into the charge return conduit, and thus back to the pump. The action of the hand control on the valve loading is such that the valve acts as a throttle valve upon the charge outlet port A², by partially closing it, thus regulating the quantity of mixture which returns to the pump. As soon as the working piston covers the charge outlet port A², the rise in pressure of the mixture trapped in the combustion chamber during the remainder of the compression stroke so acts through the port A⁴ upon the piston valve C as to overcome the net loading upon it of the springs C³, C⁴ and thereby forces it along the conduit A so that it covers the charge-return port A², and seats itself at A³, if a seating is there provided. In this position it rests during the remainder of the compression stroke and throughout the working stroke also, until exhaust commences, or the cylinder pressure acting on it is otherwise lowered to permit the spring C³ again to return it to the other end of its travel. It will readily be seen that by varying the net loading on the valve C by the hand controllable means C⁵, the valve may be set to permit just as much of the charge to return to the pump as may be desired; while on the other hand when the valve is so loaded as always to close the port A² no charge whatever is expelled

from the cylinder and the full power output of the engine is thus obtained.

Figure 2 is an example outline of an engine incorporating this invention. The crank case and pump chamber are shown at D enclosing the crank disc E with crank pin E² actuated by the connecting rod E³ attached at its small end to the engine piston E⁴ working in the cylinder B. The pump induction port is shown at G, the cylinder inlet port at G², and the exhaust port at G³. The control valve and its associated parts are lettered as in Fig. 1. It may also be observed that in Fig. 2 the valve C is shown in its closed position, the engine piston E⁴ being at the top of the compression stroke thus covering the port A² as shown.

It will be understood that this invention is applicable to forms of two-stroke engines other than that indicated by Fig. 2, which is chosen merely by way of example of the application of the invention.

It will be seen that the invention can be carried out in a variety of ways other than those illustrated, all of which have the same end in view, namely, the return to the supply source, during the compression stroke, of a portion of the working charge contained in the cylinder.

What I claim as my invention and desire to secure by Letters Patent of the United States is:—

1. In a two stroke internal combustion engine, the combination of a cylinder, a working piston therein, a combustion chamber forming part of said cylinder, a pump adapted to deliver a working charge into said cylinder, a conduit communicating at one end with said combustion chamber, and at the other end with said pump, a port formed in the side of said cylinder communicating with said conduit at a point intermediate of its ends, and adapted to be covered by said working piston during a portion of the latter's stroke, a valve located in said conduit between said port and said combustion chamber and adapted to close said port by movement under the pressure of mixture trapped in said combustion chamber after the working piston has closed said port, substantially as set forth.

2. In a two stroke internal combustion engine, the combination of a cylinder, a working piston therein, a combustion chamber forming part of said cylinder, a pump adapted to deliver a working charge into said cylinder, a conduit communicating at one end with said combustion chamber, and at the other end with said pump, a port formed in the side of said cylinder, communicating with said conduit at a point intermediate of its ends, and adapted to be covered by said working piston during a portion of the latter's stroke, a piston valve

located in said conduit between said port and said combustion chamber and adapted to over-run and to close said port under the pressure of mixture trapped in said combustion chamber after the working piston has covered said port, a seating upon which said piston valve rests pressure-tight after closing said port, and means controllable at will for regulating the extent to which said port is opened by said piston valve substantially as set forth.

In testimony whereof I have signed my name to this specification in the presence of two subscribing witnesses.

ROBERT GLADSTONE WELLS.
